UNITED STATES PATENT OFFICE.

HARRY K. BUSH AND BERTOLET F. FRAME, OF READING, PENNSYLVANIA.

SANITARY COOLER.

Application filed March 20, 1923. Serial No. 626,426.

To all whom it may concern:

Be it known that we, HARRY K. BUSH and BERTOLET F. FRAME, citizens of the United States, residing at Reading, in the county of Berks and State of Pennsylvania, have invented certain new and useful Improvements in Sanitary Coolers, of which the following is a specification.

This invention relates to improvements in water cooling apparatus and more particularly to devices adapted for installation in work-shops, factories, offices and dwellings.

One of the objects of the invention is to provide an apparatus in the form of a tank containing in plurality of the units so arranged as to use ice in an extremely advantageous and economical manner.

A further aim is in the provision of a cooling unit readily and completely separable for the purpose of cleansing the interior as occasion requires, and lined to present an enamelled surface for sanitary purposes.

These several aims, objects and purposes are accomplished by the novel construction and arrangement of parts hereinafter described and illustrated in the accompanying drawing, forming a material part of this disclosure, and in which:—

Figure 1 is a longitudinal sectional view taken through the dispensing tank, showing the relation of parts therein.

Figure 2 is a longitudinal sectional view of one of the cooling units drawn to an enlarged scale.

Figure 3 is a top plan view of the lower elements of the cooling unit in detail.

Figure 4 is a bottom plan view of the upper element and deflector.

Figure 5 is a plan view of the device drawn to a smaller scale.

As shown in the drawing, particularly Figure 1, the tank will be seen to consist of a rectangular, box-like structure generally designated by the numeral 10, having a bottom or flooring 11, and a readily movable cover 12, for the reception of blocks of ice 13, the same being disposed upon the upper surfaces of the several cooling units contained in the tank.

These cooling units each consists of a conical casing 14, the smaller end of which is directed upwardly, its walls integrally connected by a plate element 15, in one part of which is a depression 16, curved at

its bottom wall 17, and having a vertical wall 18 drilled and screw-threaded to receive a pipe or nipple 19.

The end of the nipple enters a space 20 formed in a central internal hub or lug 21 screw-threaded in its lower end to receive a pipe 22 which extends downwardly nearly to the bottom of the conical casing and has attached at its lower end a deflecting plate 23 having a raised marginal edge 24.

The lower, larger end of the casing 14 is turned outward to produce a beaded edge 25 suited to enter within an annular flange 26, formed with the base or bottom element 27 which rests upon the floor 11 of the tank.

The lower portion of the cup-shaped base 27 is formed to present an annular downwardly curved projection 28 raised at the center 29 and provided internally with a series of upstanding ridges or vanes 30, arranged to receive water from the pipe 22, distributed by contact with the center projection 29 and thereafter cause it to deflect and assume a whirling motion due to the raised vanes 30.

Ultimately the water rises past the curved edges 24 into the upper portion of the unit, which is provided with an internal lateral hub 31 to receive a discharge pipe 32, that may be joined by a union 33 to others in series, the last of which has its outlet a header 34 and discharge pipe 35 extended through the wall of the tank as shown.

Preferably there are eight units in each tank, arranged in two rows and connected by a header 36 engaged with the inlet 37.

Formed with the upper elements are projecting lugs 38 containing openings 40, similar openings 42 being formed in like lugs 39 extending out from the lower elements 27, these openings being in register so as to be connected by bolts 41 having nuts 43 adapted to clamp the upper and lower elements rigidly together, there being interposed between their adjacent faces packing rings or gaskets 44.

In operation, water entering the inlet 37 passes through the first pair of cooling units, and from thence to the intermediate units, eventually being discharged through the pipe 35.

As the water enters each unit it strikes upon the raised central element 29, is diverted

ed by the curved vanes 30 and the deflecting plate 23, thus creating an effective circulating system.

As the blocks of ice rests on top of several units it is not necessary to break the ice into fragments for the purpose of cooling the units, which, obviously are submerged in the water from the ice, the surplus water from the ice being withdrawn by an overflow pipe 10 45, a valve plug 46 near the bottom 11 of the tank providing means whereby all water in the tank can be drawn off.

As the interior of each element coming in contact with the water is porcelain lined, and 15 the several tubes used made of tin or other material of non-corrosive nature, it will be seen that cool water in a clean hygienic condition can be withdrawn at any time desired, and due to the relatively large area presented 20 by the several units, a correspondingly large quantity can be brought to the desired temperature without loss of time, a constant flow being accommodated in actual practice.

As changes of construction could be made 25 within the scope of the invention, it is intended that all matter contained in the foregoing description or shown in the accompanying drawing shall be interpreted as illustrative only and not in a limitative sense.

Having thus described our invention, what 30 we claim as new and desire to secure by Letters Patent, is:

1. A cooler comprising a tank, a series of 35 communicating cooler units having a central inlet tube open at its lower end, and a bottom closure for each unit having radiating spiral grooves receptive of the fluid passing through the tube and causing a rotary effect thereto.

2. In a cooler, a unit comprising a hollow 40 frusto-conical casing closed at its smaller upper end and having a beaded edge at its lower end, a base receptive of said edge, a packing interposed therebetween, means for

clamping said casing to the base, an annular 45 recess of semi-circular cross section in said base presenting a raised central portion, a tube extending axially downward in said casing from the closed end terminating adjacent the central raised portion of the base, a 50 lateral inlet to said casing communicating with said tube, and an outlet opposite thereto.

3. In a cooler, a unit comprising a frusto-conical casing, a cup-shaped base removably 55 engaged therewith, said base having a central raised portion, a tube directing an entering stream of fluid upon said raised portion, and a deflector secured on said tube above 60 said base, said deflector having an upturned peripheral edge disposed closely interjacent the wall of said casing.

4. In a cooler, a unit comprising a conical casing, a cup-shaped base removably engaged therewith, said base having a central 65 raised portion, means for directing an entering stream of fluid upon said raised portion, means in said base to cause a whirling effect of the entered liquid, and a deflector plate secured to said liquid entering means adjacently above said base.

5. In a cooler, a unit comprising a conical casing, a cup-shaped base removably engaged therewith, said base having a central raised portion, means for directing an entering stream of fluid upon said raised portion, a tube depending axially in said casing, there being a lateral inlet communicating therewith, a deflecting plate fixed on the end of said tube spaced above said base, and a plurality of curved ridges in the cavity of said base adapted to cause liquid entering through said tube to assume a whirling motion below said deflecting plate.

In testimony whereof we have signed our 85 names to this application.

HARRY K. BUSH.
BERTOLET F. FRAME.
